UNITED STATES PATENT OFFICE

FRANCIS L. STEPHENSON, OF AMBLER, PENNSYLVANIA, ASSIGNOR TO BETHLEHEM STEEL COMPANY, A CORPORATION OF PENNSYLVANIA

SILO

Application filed December 3, 1930. Serial No. 499,785.

My invention relates to improvements in silos.

One of the objects of the invention is to construct silos or bins of interlocking sections which do not require the use of separate fastening means to prevent separation thereof.

Another object of the invention is to provide a group of silos which is especially adaptable for the storage of material such as coal and the like.

The novel features of my invention will be more fully understood from the following description and claims taken with the drawings in which:

Fig. 1 is a side elevation of my improved silos;

Fig. 2 is a cross sectional view taken on line 2—2 of Fig. 1;

Fig. 3 is an enlarged sectional view of a plurality of the interlocked sections which comprise the wall structure of the silos; and

Fig. 4 is an enlarged sectional view of one of the interlocked joints.

Referring to the drawings more in detail, 10 designates the large silos, and 11 designates a small silo, the walls of which are formed by a portion of the walls of the large silos 10.

The silos are preferably supported on girders 12 which are in turn mounted on suitable beams 13, supported on columns 14 so that vehicles, such as trucks, wagons, or the like may pass beneath the silos. Chutes 15 and 16 are provided to convey the material from the silos to the vehicles.

Each of the large silos 10 is constructed of a plurality of longitudinal metallic sections 17, an enlarged sectional view of a plurality of such sections being shown in Fig. 3, and are preferably mounted on a circular member 18 which is angular in cross section and which is supported on the girders 12. The member 18 is so formed that its upper turned flange 19 will engage the outer surface of the sections 17. A concrete floor is preferably provided in each of the large silos and also in the smaller silo. The floor in the large silos is formed so that it will bind the outer surface of the sections 17

against the members 18 and thus firmly support the lower ends of the silos.

Each of the sections 17 comprises a web portion 20, having inclined sides 21 and 22, each of which are flanged at their outer ends and are provided with a hook-like member 23 and an arcuate guard member 24 forming therebetween a pocket 25, as clearly shown in enlarged section in Fig. 4. The pocket 25 has a longitudinal opening 26 between the ends of the hook flange and the guard flange which is somewhat less in width than the greatest internal width of the pocket.

The hook member 23 is provided with an elongated head 28 which is sufficiently shorter than the extreme width of the pocket 25 so that the sections will slide freely into place and which is longer than the width of the opening 26 so that the sections can only be placed in position by inserting the head 28 of the hook member 23 of each section into the end of the pocket 25 of the adjacent section. Therefore due to the head 28 of each section engaging the pocket 25 of the adjacent section a double lock is provided to prevent the sections from being separated horizontally.

The inner face of the guard member 24 is substantially concentric with the outer segmental cylindrical face of the hook member 23 on the adjoining section so that the sections may be turned one on the other to any suitable position without changing the strength of the interlocks.

These sections are especially adaptable to the construction of circular silos, as the joints are very adjustable, so that it is not necessary to have different preformed joints for each size of silo, as would be the case if other types of well known joints were used. Further a silo constructed of this type of sections, which may be termed self-sustaining, is exceptionally strong as the interlocks which prevent lateral displacement of the sections extend throughout the length of the sections. Further owing to the construction of this joint there is a double lock between each section as well as three points of contact as clearly disclosed in Fig. 4. Therefore very strong joint as well as a relatively tight joint is pro-

vided between the sections 17. An additional feature of the sections 17 is that there are no joints on the outermost surface to interfere with connecting the silos together or to interfere with the placing of bands around the silos.

The sections are assembled by placing the head 28 of each section into the end of the pocket 25 of the adjacent section and sliding 10 one of the sections longitudinally into place and continuing this procedure until the silo is completed.

After the sections have been assembled a circular member 30, similar to member 18, 15 is preferably placed over the upper end of the silo with one of its flanges engaging the upper surface of the ends of the sections 17 and the other flange extending downwardly around the outer surface of the silo so as to hold the sections 17 in proper alignment.

Strengthening bands 31 may be placed around the silo intermediate the upper and lower members 18 and 30.

To dismantle the silo it is only necessary 25 to remove the member 30, and the bands 31, if they have been used, and slide the sections 17 longitudinally of each other until all the sections have been removed. Therefore my silo is very adaptable where it is desired to 30 provide a structure which may be moved from one location to another, as conditions require, as the main parts thereof can be easily dismantled and reassembled without any difficulty.

35 In the drawings I have shown a plurality of large silos constructed in such a manner that a small silo is formed intermediate said silos. The construction of the four large silos are as described above and they are 40 connected together by suitable fasteners such as rivets 32 being placed in the webs of the sections 17 where the silos abut each other. Filler plates 33 are provided intermediate the bands 31 and the members 18 and 30 where it 45 is desired to make a tight joint between the silos 10, so that the small silo 11 may be used for fine material. Circular angle members 35 are preferably attached to each silo and plates 36 are attached thereto to further 50 strengthen the structure.

It will therefore appear from the above 55 that I have invented a silo which is particularly adaptable for the storage of bulk material. It will also be seen that a silo constructed in accordance with my invention can be easily assembled and dismantled without destruction to the main members of the structure. This feature is important in cases 60 where it is desired to move the structure from one location to another.

While I have shown my invention in but 65 one form it will be obvious to those skilled in the art that it is not so limited, but is susceptible of various other changes and modifications without departing from the spirit

thereof, and I desire, therefore, that only such limitations shall be placed thereupon as are imposed by the prior art or as are specifically set forth in the appended claims.

Having thus described my invention what 70 I claim as new and desire to secure by Letters Patent is:

1. A land silo for storage purposes comprising vertical metallic wall sections, each section having integral interlocks along each vertical edge thereof constituting a pocket and a hook the hooks of each section entering the pockets of adjacent sections and the pockets of each section receiving the hooks of adjacent sections to interlock said sections against horizontal displacement to form a closed wall providing a storage space above ground within said wall. 80

2. A circular land silo for storage purposes comprising a plurality of longitudinal sections to constitute a wall, each section comprising integral interlocks along its vertical edges and being slidably connected to the adjacent section and interlocked against lateral displacement with respect to one another, a foundation supporting said wall mounted on substantially the surface of the ground comprising a ring member having means to restrict the radial displacement thereof. 90

3. A land silo for storage purposes comprising a plurality of vertically disposed longitudinal, metallic sections, interlocked at their vertical edges, each section comprising integral interlocks along its vertical edges to form a closed wall providing a storage space above ground within said wall. 100

4. A land silo for storage purposes comprising a plurality of vertically disposed, longitudinal, metallic sections, each section comprising integral interlocks along its vertical edges, said sections being interlocked at their vertical edges by a sliding connection longitudinally thereof to form a closed wall providing a storage space above ground within said wall. 110

5. A land silo for storage purposes comprising a plurality of vertically disposed, longitudinal, metallic sections, interlocked along their vertical edges, each section comprising integral interlocks along their vertical edges and having portions offset relative to each other, the interlocked sections constituting a wall structure disposed staggerwise, in a plurality of vertical planes providing a storage space above ground within said wall. 115

6. A land silo for storage purposes comprising a plurality of vertically disposed, longitudinal, metallic sections, interlocked along their vertical edges, each section comprising integral interlocks along their vertical edges offset from the remaining portions thereof, the interlocked sections constituting a wall structure disposed staggerwise in a 125 130

plurality of vertical planes the interlocked portions of the sections occupying an inner plane providing a storage space above ground within said wall.

5 7. A land structure for storage purposes comprising a closed wall of sheet interlocked piling providing a storage space above ground within said wall.

10 8. In a land silo structure for storage purposes, the combination of vertically disposed, longitudinal metallic wall sections, each section comprising a web and diverging flanged sides, and locking members integral with the flanges of said sides for interlocking said sections together to form a closed wall providing a storage space above ground within said wall.

15 9. In a land silo structure for storage purposes, the combination of vertically disposed, longitudinal trough shaped sections, each section comprising a web portion and side portions and outwardly extending flanges at the margin of said sides and interlocking means, comprising a hook member and a guard member, integral with each of said flanges to form 20 a closed wall providing a storage space above ground within said wall.

25 In testimony whereof I hereunto affix my signature.

CERTIFICATE OF CORRECTION.

Patent No. 1,913,174.

June 6, 1933.

FRANCIS L. STEPHENSON.

It is hereby certified that error appears in the printed specification of the above numbered patent requiring correction as follows: Page 2, after line 60, insert the following paragraph:

As will be evident from the above, the silos shown are not subterranean. While it is obvious that the essential inventive thought would not be avoided by the piling sections being more or less imbedded in the earth, I believe it by far the greater part of the silo proper, that is, the containing portion of the silo, should be above the surface of the ground.

And that the said Letters Patent should be read with this correction therein that the same may conform to the record of the case in the Patent Office.

Signed and sealed this 12th day of December, A. D. 1933.

F. M. Hopkins
